UNITED STATES PATENT OFFICE.

ANDREW WESTLING, OF MINNEAPOLIS, MINNESOTA, ASSIGNOR TO CONCRETE ELEVATOR COMPANY, OF MINNEAPOLIS, MINNESOTA, A CORPORATION OF MINNESOTA.

APPARATUS FOR REMOVING GRAIN DOORS.

Application filed January 6, 1928. Serial No. 244,905.

This invention relates to apparatus for assisting in the unloading of grain from freight cars and especially to apparatus for removing the usual wooden grain doors from the doorways of the box cars.

It is the main object of my invention to provide simple economical and highly efficient apparatus which will quickly remove grain doors of common type from the doorways of box cars without injuring the doors.

A further object of the invention is to provide grain door removing apparatus, which will cause the grain doors to be moved inwardly away from the doorway, upwardly over the top of the grain and to be swung in such a manner that one end will be disposed adjacent the doorway whereby an operator can easily eject the door from the car.

Another object is to provide in apparatus of the class described mechanism adapted to co-operate with operating mechanism provided at this time in most grain elevators of any size, the co-operation of said mechanisms being adapted to quickly remove the grain doors from the cars with a considerable saving in time and labor over methods formerly employed.

These and other objects and advantages of the invention will be apparent from the following description made in connection with the accompanying drawings in which like reference characters refer to similar parts throughout the several views and in which,

Fig. 1 is a vertical section taken through a box car disposed in the unloading shed of an elevator showing a preferred embodiment of my invention applied for operation upon one of the grain doors;

Fig. 2 is a perspective view illustrating the manner in which a grain door is removed from the doorway of a box car and lifted over the top of the grain in the car and simultaneously tilted to dispose one end thereof properly for ejection of the door from the car; and

Fig. 3 is a perspective view showing the construction of my extricating hook.

In the drawings, a portion of an elevator shed S is illustrated having the track T ex-

tending thereunder over which the freight cars are adapted to be moved for unloading. One of the heavy horizontal beams B of the elevator building is illustrated as extending across the top of shed S and a box car C of common type is shown standing on track T in position to unload to one of the elevator pits P. The box car C is illustrated as being filled with grain up to a heavy capacity level L and a plurality of grain doors 4 of common type are secured in the usual manner across the doorways 5 of the car, said grain doors being nailed or otherwise secured from the inner side of the car. Obviously, the pressure of grain against the doors 4 is very great and considerable force must be exercised to remove the doors while the grain is in the car.

In my apparatus, a flexible member 6 is employed passing over a pulley 7 supported from beam B substantially above the pit P and also passing over a pulley 8 also supported from the beam B and disposed adjacent the outer side of the shed and vertically aligned with a point outwardly disposed of the left side of the box car C. Flexible member 6 as shown extends substantially horizontally across the top of the shed and downwardly after passing over pulley 8 and over a third pulley 9 which may be supported from the vertical wall of shed S at a height slightly below the top of the box car. Cable 6 from pulley 9 is extended transversely into the box car, passing through the aperture defined by the top of the doorway 5 and the uppermost grain door 4 at the side of the car at which unloading will not take place. The end of flexible member 6 is connected to a substantially L-shaped extricating hook 10 having an elongated flat body portion 10^a and a wedge shaped head 10^b, said head extending substantially perpendicular to said body portion. The head 10^b is preferably provided with two or three inclined teeth 10^c and further has a thickened portion 10^d which may be struck with a hammer to permit the wedge shaped end 10^b to be driven between a pair of successively arranged grain doors 4 at the unloading side of the car and be-

neath the lower edge of the uppermost grain door. Fig. 1 illustrates the manner in which my extricating hook is applied in position to remove the top grain door at the right hand side of the car.

The opposite end of flexible member 6 may extend downwardly and terminate in a small hook 6^a which may be adjustably secured to a chain or other flexible member 12. The chain illustrated is utilized simply to facilitate the connection of flexible member 6 with winding means for actuating extricating hook 10. Suitable winding mechanism is provided connected to cable 6 and I prefer to use winding mechanism which will move cable 6 a predetermined distance and automatically stop the winding action and which further may be caused to wind when the cable 6 has been manually pulled out a desired distance to permit extricating hook 10 to properly engage another grain door. While many types of winding mechanism can be utilized as an element of my apparatus I prefer to use the mechanism illustrated in Fig. 1, which is a well known mechanism for operating power grain shovels. This power mechanism indicated by the letter M is provided with a winding reel 13 to which the upper end of a cable or other flexible member 14 is secured. As shown, mechanism M is supported on the beam B and is connected to a power shaft 15 and the cable 14 extends downwardly from winding reel 13 and under a pulley 16 which is mounted on a suitable support 17 at a height substantially equal to the height of the floor of box car C. The end of cable 14 is connected to the lower end of chain 12 and as above described chain 12 has its upper end releasably connected as desired to one end of cable 6. A stop member 18 of any suitable form and of greater size than the cross section of chain 12 may be secured to the chain for a purpose to be later described.

It will be obvious that various operating mechanisms either manual or automatic may be utilized for pulling cable 6 the requisite distance to remove the grain door and I prefer to utilize an automatic winding mechanism, such as the power shovel operating mechanism M, illustrated in Fig. 1. Since this mechanism M is a well known mechanical device on the market at this time it is not necessary to describe the construction thereof, but its functions may be briefly described as follows:—

The power shaft 15 is connectible with the winding reel 13 by a suitable clutch adapted to be thrown in by a short tug on the cable 14. Winding reel 13 then begins to function and will continue until cable 14 is again pulled which releases the clutch. Stop member 18 or any other suitable stop will automatically pull the clutch out of engagement to arrest the winding action when it engages the pulley bracket, failing to pass through the pulley

16. Thus, by regulating the distance of the chain or other flexible member 12 between stop 18 and the pulley, the winding action of mechanism M is determined.

Operation.

70

The operation of my apparatus, although perhaps obvious from the foregoing description may be briefly summarized as follows:

The extricating hook 10 and the outer end of cable 6 are passed through the box car C 75 and the wedge shaped head 10^b of said hook is driven between the lower edge of the upper right hand grain door and the adjacent edge of the next lower grain door. This is easily facilitated by hammering upon the heavy portion 10^d of hook 10. The hook is placed adjacent one end of the door and when properly applied has its flat body portion 10^a disposed flush against the outer side of the top grain door 4. Hook 6^a is then connected with one of the links of chain 12, the cables 14 and 6 being first stretched to connect the same with a minimum of slack. The cable 14 or the chain 12 may then be pulled in the direction of car C to throw in the clutch of mechanism M. Winding immediately takes place and the power derived is more than ample to quickly extricate the door 4 from its engagement with the inner sides of the doorway 5. Since pulley 9 is disposed slightly above the height of the top edge of the grain door and since cable 6 extends transversely of the freight car the upper grain door will be rapidly moved backwardly and upwardly sliding over the top of the grain in the car and not being obstructed by said grain. Simultaneously with the movements described, the door will swing from end to end the right hand end swinging faster than the left hand end. At the completion of the winding action of mechanism M the left hand end of the door will be directed towards the opening of the doorway in convenient position for an operator to quickly eject the door from the car.

Because of the structure of my extricating hook 10 and its engagement with the door and because of the manner in which the pull is exerted on cable 6 the door will be torn away from the doorway without injury or fracture and may be utilized again.

To reset the device to operate upon the next grain door it is only necessary for an operator to reach into the car from the unloading side, move the hook and cable through the car and again drive the wedge shaped head 10^b of the extricating hook between the lower edge of the top grain door and the adjacent edge of the lower door. A taut connection is then again made between the hook 6^a and the chain 12 and the removal of the door will quickly take place when the cable is again tugged. The movement of cable 6 is always sufficient to cause the grain door to be completely with-

drawn from the doorway and moved upwardly and transversely of the car over the grain.

The inclined teeth 10^a formed on the inner edge of the wedge shaped head 10^b of my hook prevent the hook from slipping out of engagement with the lower edge of the upper door, in other words, from being drawn around the outer side of the door.

10 From the foregoing description it will be seen that I have invented a simple but highly efficient apparatus for very quickly removing grain doors, which will positively pull the door from the doorway over the top of the grain in the car, leaving the door in position to be ejected from the car and accomplishing the functions previously described, without damaging the door.

15 The device has been extensively tested in a large elevator and has been found highly efficient for the purposes enumerated, said extensive tests having conclusively shown that box cars may be unloaded with my apparatus in two-thirds the time required 25 where other types of apparatus for removing grain doors are employed.

It will, of course, be understood that various changes may be made in the form, details, arrangement and proportions of the parts 30 without departing from the scope of the invention, and that other mechanisms for winding or operating the cable 6 may be employed although the mechanism M , illustrated, is preferred since most grain elevators are at 35 this time equipped with the same.

What is claimed is:—

1. Apparatus for removing grain doors from freight cars having in combination, a relatively stationary support, a guide member 40 mounted on said support in position to be disposed at one side of a freight car opposite a doorway thereof and at a height somewhat above the upper edge of the top grain door at said side, a flexible member passing 45 through said guide member and adapted to be extended through the car transversely thereof and to the opposite side, an extricating hook connected to the end of said flexible member and adapted to be disposed below the lower 50 edge of the top grain door at said opposite side of the car, and means for transmitting 55 pull upon said flexible member to withdraw said top grain door and cause the same to move inwardly and upwardly over the grain within the car.

2. Apparatus for removing grain doors from freight cars having in combination, a relatively stationary support, a guide member 60 mounted on said support in position to be disposed at one side of a freight car opposite a doorway thereof and at a height somewhat above the upper edge of the top grain door at said side, a flexible member passing 65 through said guide member and adapted to be extended through the car transversely

thereof and to the opposite side, an extricating hook connected to the end of said flexible member having an elongated flat body portion adapted to be disposed flush against the outer surface of the top grain door at said 70 opposite side of the car, and also having an angularly disposed head adapted to be positioned beneath the lower edge of said last mentioned grain door, and means for suddenly transmitting pull upon said flexible 75 member to withdraw said grain door and cause the same to move inwardly and upwardly over the grain within the car.

3. Apparatus for removing grain doors from freight cars having in combination, a 80 relatively stationary support mounted near a car track, a guide member mounted on said support in position to be disposed at one side of a freight car opposite a doorway thereof and at a height somewhat above the upper 85 edge of the top grain door at said side, a flexible member passing through said guide member adapted to be extended through the car transversely thereof and through the opposite side, an extricating hook connected to the 90 end of said flexible member and adapted to be disposed below the lower edge of the top grain door at said opposite side of the door, said hook extending inwardly, and winding mechanism connected to said flexible member for withdrawing said grain door and causing the same to move inwardly and upwardly 95 over the grain within the car.

4. Apparatus for removing grain doors from freight cars having in combination, a 100 relatively stationary support mounted near a car track, a guide member mounted on said support in position to be disposed at one side of a freight car opposite a doorway thereof and at a height somewhat above the upper 105 edge of the top grain door at said side, a flexible member passing through said guide member adapted to be extended through the car transversely thereof and through the opposite side, an extricating hook connected to the 110 end of said flexible member and adapted to be disposed beneath the lower edge of the top grain door at said opposite side of the car, winding mechanism connected to said flexible member for withdrawing said grain 115 door and causing the same to move inwardly and upwardly over the grain within the car, and means for automatically controlling said winding mechanism to cause said hook to be moved through a predetermined distance.

5. Apparatus for removing grain doors from freight cars having in combination, a relatively stationary support mounted near a car track, a guide member mounted on said support in position to be disposed at one side of a freight car opposite a doorway thereof and at a height somewhat above the upper edge of the top grain door at said side, a flexible member passing through said guide member 125 and adapted to be extended through the car 130

transversely thereof and through the opposite side, between the top of said ear and the top of the upper grain door at said side, an extricating hook connected to the end of said flexible member, and having a flat body portion adapted to be disposed flush against the outer surface of said last mentioned grain door, and also having an angularly extending wedge-shaped head provided with rear-

wardly inclined teeth, said head being adapted to be driven beneath the lower edge of said last mentioned grain door, and means for transmitting pull upon said flexible member to withdraw said last mentioned grain door and cause the same to move inwardly and upwardly over the grain within the ear. ¹⁰

In testimony whereof I affix my signature. ¹⁵

ANDREW WESTLING.
